CLAIM

The ornamental design for a vaporizer balloon as shown and described.

DESCRIPTION

1.1 : Front

1.2 : Perspective

The design is limited to features of shape and configuration of the vaporizer balloon as shown in the reproductions; Fig. 1.1 is a front view of the vaporizer balloon; Fig. 1.2 is a perspective view of the vaporizer balloon in an inflated state; the parts shown by broken lines do not form part of the claimed design.
